METHOD AND SYSTEM OF REGULATION

Allen M. Rossman, Wilmette, Ill., assignor to Rossman, Sargent & Lundy Patents Corporation, Chicago, Ill., a Corporation of Illinois

Application December 3, 1929. Serial No. 411,336

19 Claims. (Cl. 236—14.)

My invention relates to regulating systems.

While the specific embodiment herein shown and described is a system of combustion control for boilers it is understood that the invention is broader in its application than this specific use.

In combustion control the first factor to be considered is the load, or overall rate of heat development. This may be assumed to be represented by the amount of steam delivered at a given pressure, where the boiler efficiency is constant. Or, if the steam delivery nozzles are set at a given setting and combustion is proceeding at a given rate, the deviation of load from a fixed value may be considered as reflected in variations of steam pressure. Thus I assume a mean steam pressure and deal only with variations therefrom.

It is always assumed that so long as boiler pressure remains constant, the load is being properly carried.

Now, in considering how to relate combustion, namely, union of air and fuel to load, it is to be observed that the composition of atmospheric air is substantially a constant, whereas the composition of fuel may vary. Hence it is customary to relate steam delivery to air flow to the combustion chamber. That is to say, the factor in combustion which is most inflexibly related to load is air delivery to the combustion chamber. Or, the air flow to the combustion chamber may be related to the percentage of carbon dioxide in the flue gases.

In my system of combustion control I relate air flow to load. This may be done by measuring the steam flow and controllably varying the air supply as a function of steam flow; or it may be done by an approximate initial adjustment of air delivery to steam load and a deviation from said general relation by an adjustment under the control of steam pressure.

In my preferred embodiment I assume a certain definite proportion or relation between pounds of steam delivered per unit of time at a given pressure, and pounds of air supplied per unit of time at a given barometric pressure.

A certain air flow per unit of time will support proper combustion of a certain amount of fuel per unit of time, other things remaining constant. While the fuel (usually, but not necessarily, coal) may be considered of a uniform composition for initial setting of the fuel feeding means, it varies, and perfect combustion will not result when the assumed relation does not prevail. Therefore, an adjustment of the ratio must be made.

The simplest method of determining what adjustment is required is by reference to an efficiency

meter—for example, a CO₂ meter. When the efficiency meter reports too little CO₂ per unit volume of fuel gas the fuel feeding rate is increased, relative to the air supply, or vice versa.

Now I am aware that it has heretofore been proposed to make the rate of fuel feed dependent upon the rate of air feed. I wish to point out that I do not treat the fuel feed as a dependent variable and make it hunt the rate of air feed, but start with the assumption of a proper ratio of fuel to air and deal only with deviations therefrom just as I treat the ratio of load to air flow as an assumed mean ratio and deal only with deviations from said ratio.

This simplifies the entire problem by permitting one to adjust simultaneously the fuel and air for changes in load, as reflected in variations of gauge pressure from a selected value.

Now in particular installations the problem of air supply is divided between induced draft and forced draft. Again I start with an assumed ratio or mean and deal with variations therefrom as detected by a furnace pressure gauge. Hence, in controlling induced or forced draft I step up or down the two draft controllers (whatever they may be) simultaneously, on the assumption of the proper ratio, and let the adjustment between them be made under the control of the furnace pressure gauge, or a gauge which is sensitive to deviations from the proper ratio of induced to forced draft pressure.

Also in particular installations the fuel feed problem may be complicated by the burning of powdered coal, in that the feeding of powdered coal into the furnace is to be promptly changeable with change in rate of main air flow, where-as bringing up and grinding of fuel is a matter which must also be adjusted.

The relation of bringing up and grinding of coal for feeding of powdered coal to the furnace is assumed to have a definite ratio and any deviation from said ratio may be detected by variation from a mean in the amount of powdered coal available to the feeder. This may be detected by weight and adjustment made accordingly, if desired. Generally the coal grinder maintains a fairly large accumulation of powdered coal which will take care of temporary deviations in ratio, but automatic adjustment is desirable.

Now it is to be observed that within the broad aspects of my invention any or all of the steps of my method may be performed by hand. For example, with the assumed mean ratio of steam to air to fuel, any desired increase in steam de-

livery may be made immediately by simultaneous adjustment of air and fuel-feeding rates.

The deviation required to secure accurate correspondence of results, i. e., to hold up or down gauge pressure, is made by an adjustment regulated in accordance with the steam pressure gauge. Thus, increase of delivery of the boiler may be easily secured by selecting a higher pressure point on the gauge as the mean, or when orifice or valve control is employed to regulate the proportion of load of each boiler, such orifice or valve may be adjusted to control the actual rate of delivery and the rate of fuel and air supply changed accordingly to raise or lower the gauge pressure.

Then, as between the proportions of fuel and air I may make an adjustment to secure the desired efficiency of combustion, as detected by the CO₂ meter.

Also, as between induced and forced draft, I may make the necessary differential adjustment as may be indicated as desirable by the furnace pressure gauge or other means for comparing forced to induced draft.

Likewise, in powdered coal installations I may thus make the necessary adjustments as between powdered coal delivered and fuel supplied and ground, in accordance with deviation of the feeding of powdered coal from a predetermined value.

Proceeding upon the fundamental concept of regulation as above I provide, according to the present invention, suitable means for carrying out the process in practice. The first problem in this connection is to provide a practical, workable way for regulating the air delivery. I secure this by driving a fan at variable speed.

Now it is known to drive a fan at a fixed speed and regulate the delivery by means of dampers; and it is known to drive a fan at variable speed by a wound rotor A. C. motor. In power generating plants, to which my invention is peculiarly applicable, fans of great size are required. For example, a fan requiring 500 H. P. is not at all unusual. It is highly desirable to supply the major part of the power to such apparatus by A. C. as that can be received through transformers directly from the main generators, whereas the translation thereof to D. C. would involve large losses and large investment costs.

I have developed an A. C. variable speed drive as disclosed in my co-pending case, Serial No. 275,641, wherein the major part of the motion and power is supplied by an A. C. squirrel-cage motor and the supplementary increase or decrease of motion and power is supplied or taken up by a D. C. machine acting as either a motor or as a generator. This drive is capable of operating at any predetermined speed within its range, under the control of a rheostat setting. That is to say, it will give a fixed speed for each rheostat setting so that its performance may be accurately related to the setting of the rheostat. This is an important aspect of the device. Its efficiency over known schemes of variable speed drive, particularly for large power, is also an important aspect of the same.

With this variable speed drive and simple rheostat adjustment, any desired air delivery and any desired fuel feed may be accurately attained. Likewise, accurate adjustment as between induced and forced draft is also attainable by this drive.

Next, in order to secure suitable adjustment of the rheostats, for air supply or fuel supply, or

adjustment of any mechanical or electrical device to control the rate of operation of any element entering into combustion control, I have been compelled to devise a regulating system.

This regulating system is novel in itself, independent of its particular function herein. That is to say, I have provided a new regulating or control system per se which involves both a novel method of operation and a novel means to carry out the desired method of operation.

According to my novel regulating or relay system I control a desired consequent or plurality of consequents, according to the directions of one or more controls. The regulating system and method are applicable to any problem where one or more elements are to be regulated, according to conflicting requirements of one or more controls.

Now, in a boiler control system, the controls are, for example, gauge pressure and efficiency of combustion.

The consequents are, for example, absolute values of air feed and fuel feed and the ratio of air feed to fuel feed. Also, for example, the control may be furnace pressure, or variations from a predetermined ratio between forced and induced draft, and the consequent may be the relative speeds of the forced draft fan and the induced draft fan, or the relative rate of forced draft air supply to the rate of induced draft exhaust.

In a more comprehensive system the controls may be all of the above recited or the consequents all of the above recited, and may be inter-related.

Where such plurality of controls and consequents are to be inter-related I proceed as follows:

First, for any change in the main control, i. e., gauge pressure, I make a definite step of change in both main consequents, namely, air supply and fuel supply, according to the initially assumed relation.

For example, if the gauge pressure drops, I advance the absolute value of both fuel and air feed rates but keep them proportioned according to a fixed assumed relation. As soon as this definite step of change has been completed I wait a predetermined interval to let the change take effect with respect to gauge pressure and to see if the assumed relation between fuel and air is proper. I then test the fuel to air relation to see if it is proper; if not, then an adjustment of the ratio is made, as by varying fuel in respect to air.

Then I again test the main control, i. e., the gauge pressure, to see whether the aforesaid fixed step is sufficient. If it is not, then I take another definite step of increase or decrease of air and fuel in the initially assumed relation and again wait to see both whether the relation is proper and whether the degree of adjustment is proper.

My method of adjusting the consequents to the controls is based upon taking substantially fixed steps, which are adjustable, at timed intervals, which are adjustable, but after being adjusted remain fixed.

I test the controls in succession. I may test them if they conflict or if they do not conflict, simultaneously or in succession. Hence, a consequent which is subject to two controls which may conflict can follow in an orderly way the conflicting requirements, even though they conflict. By thus successively and alternately testing and adjusting I do not require any of the

elaborate means or interlocks such as have heretofore been required.

The testing and adjusting means of my invention is notably simple. The controls are simple 5 contact needles swinging either way from a neutral position to make contact. By suitable contactor relays, positive or negative potential for positive or negative adjustment, respectively, of all related consequents, is provided. Since 10 the controls may have conflicting requirements, so that both positive and negative potentials might tend to be applied to the same consequents at the same time, I interpose a switching device, herein designated as the timing controller, 15 which, in an orderly manner and for definite periods, gives each control complete domination over all its related consequents. The interval of waiting may be interposed at any point and it may be made as long or as short as desired.

20 This switching device is made up in the preferred form of my invention as a series of rotary segments with adjustable stationary contactors. Obviously, a wide range of equivalents is possible with my switching device, but the specific form 25 of the switching device above is simple, inexpensive and easily constructed, operated and adjusted.

Now, in order to acquaint those skilled in the art with the manner of constructing and operating a device embodying my invention I shall describe, in connection with the accompanying drawings, a specific embodiment of the same and the manner of use thereof.

In the drawings herein, similar reference numerals refer to similar parts.

Figure 1 is a diagram of a boiler having the various operating and control elements indicated in connection therewith.

Figure 2 is a diagram of the connections involved in the system and method of control.

Figure 3 is a front elevational view of the commutating or switching device and

Figure 4 is a transverse section taken on the line 4—4 of Figure 3.

45 Referring first to Figure 1, I have shown herein diagrammatically the main operating and control parts for a power generating boiler 1, which may be of any suitable type. This boiler 1 is provided with a steam pressure gauge 2 of a type suitable to operate the electrical controls hereafter to be described. The fire box 3 is shown in this case as fired with powdered coal through two sets of nozzles, 4 and 5 respectively, having individual means for supplying powdered 50 coal thereto. While the invention is herein shown as embodied in a steam generating plant employing powdered fuel it is to be understood that this is merely by way of illustration and not of limitation.

60 The furnace 3 is fed with coal and air by duplicate apparatus for each, mainly for the sake of reliability. The nozzles 4 and 5 receive their mixture of powdered coal and air through a passageway 6 from the coal pulverizer 7, this mixture being moved by the exhauster 8 driven by a suitable driving motor 9.

65 As illustrated on the right hand side of Figure 1, fuel from a suitable source of supply is delivered by a pair of coal feeders 10—10 from the hoppers 13. The feeders 10 are driven by feeder motors 12, the speed of these motors being regulable in order to control the rate at which fuel is supplied to the boiler. This motor 12 may be a variable speed motor, for example, a D. C. motor or it may be a variable

speed A. C. drive, hereafter described. The pulverizer 7 has a grinding mill 14 driven by a variable speed electrical drive 15. The exhauster motor 9 may be driven at substantially constant speed although this may be a variable speed 80 motor or drive if desired.

Primary air for carrying the pulverized fuel is supplied to the pulverizer 7 through the duct 16, this duct leading from the forced draft supply duct 17 leading from the air heater 18. A 85 controlling damper 19, operated by a pilot motor 20 controls the air supply through the duct 16. In other words the damper 19 regulates the primary air supply.

The nozzles 4 are fed with fuel and primary air by apparatus shown at the left of Figure 1, which is a duplicate of that shown at the right of Figure 1 and has primed reference numerals applied thereto to designate like parts.

90 The main air supply to the furnace 3 is furnished by a pair of forced draft fans 22 and 22', driven by variable speed drive mechanisms 23, 23'. These fans 22 and 22' deliver air through the conduits 24, 24' to the air heater 18, 18', which is heated by the exhaust gases after they 100 pass through the economizer 25.

After the air passes out of the air heater 25 into the conduits 17, 17', the major volume of the same is delivered to the furnace 3 through the secondary air supply ducts 26, 26'. The main 105 volume of air is supplied through the ducts 26, 26', the air supplied through the ducts 16, 16' being insufficient to support complete combustion of the fuel and serving rather as a carrier of the fuel to bring it into the furnace 3 where 110 it mixes with the main air supply which is required to support combustion.

The products of combustion pass up through the tubes of the boiler 1 then through the economizer 25 then through the air heater 18 and 115 thence to the conduit 27 leading to the stack 28.

The conduit 27 is divided into two channels, 29, 29', leading to the exhaust fans 30, 30', which are driven at any desired speed within limit by the variable speed driving devices 32, 32' which 120 are of a character similar to the devices 23, 23' for driving the forced draft fans.

The pressure of air in the furnace is preferably maintained at a pressure slightly below atmospheric generally in the neighborhood of .01 125 of an inch of water. The pressure prevailing in the furnace 3 is indicated upon the furnace pressure gauge 23. When the ratio of induced to forced draft is proper the above stated pressure, slightly less than atmospheric, is maintained 130 within the furnace 3.

Obviously, in order to vary the rate of steam delivery by the boiler 1, the amount of heat developed in the furnace must be likewise varied, assuming a constant condition of efficiency and 135 the like in the boiler and the furnace. Such variation in developed heat means variation of the chemical union of fuel and oxygen of the air. In order to maintain efficient combustion it is necessary that the ratio of fuel to air be maintained at a proper value. Variation of the heat developed, therefore, must be accomplished by simultaneous variation of air supply and fuel supply in order to maintain the efficiency of 140 combustion which is desired. This problem of varying simultaneously the air and fuel is, in the present instance, complicated by the necessity for maintaining the proper ratio of forced to induced draft, or vice versa.

145 The efficiency of combustion is determined by 150

a carbon dioxide meter, generally termed a CO₂ meter; this is indicated at 34 as connected to the conduit 27, through which the products of combustion flow to the stack.

- 5 To obtain the best possible combustion efficiency from the boiler it is necessary to mix with the fuel as nearly as possible the correct amount of air to provide two parts of oxygen for each part of carbon in the fuel. If too much air is furnished too much heat is wasted up the stack. If too little air is furnished, insufficient oxygen is supplied and not all the fuel is burned. Air in excess of the amount necessary must be supplied to insure that, so far as possible, each part 10 of carbon comes in contact with the required amount of oxygen. This is checked by measuring the percentage of CO₂ in the flue gases, this percentage being in the neighborhood of 12% to 14% under the best practicable conditions.
- 15 20 With the boiler in continuous operation and connected to a steam main not shown, for delivery of steam to a turbine or the like, the load may be assumed to be properly carried, so long as the steam pressure gauge indicates that an adequate pressure is maintained. That is to say, so long as the steam pressure gauge indicates that a constant pressure is maintained the rate of combustion is proper for the load carried by the boiler.

Any deviation of the ratio of rate of fuel combustion to load will be evidenced by rise or fall of steam pressure which will at once affect the gauge 2.

Therefore, with a given speed of the induced draft fans and the forced draft fans for passing a predetermined amount of air through the fire box per unit of time and with a proper setting of the coal feed 10 and damper 19 to supply the necessary fuel for union with a predetermined volume of air and the steam pressure gauge 40 indicating the desired pressure, the boiler may be assumed to be in proper operation, carrying its load.

If the boiler pressure should drop, indicating that the rate of heat development is not as great as required, fuel and air feed should be simultaneously increased in such proportion as to maintain substantially a predetermined ratio of air to fuel. This is then to be carried out by the automatic mechanism diagrammatically shown in Figure 2.

If the resultant ratio of air to fuel is not exactly right to secure the desired percentage of carbon dioxide in the fuel gases as measured by the meter 34, a correction of the ratio of air to fuel feed must be made. Also, in increasing the rate of combustion, the induced draft and forced draft must be simultaneously increased in such a manner as to maintain the furnace pressure at a proper value as determined by the furnace pressure gauge 33.

Now it can be seen that the automatic control system is called upon to vary at least three things, namely, forced draft, induced draft and coal feed, while maintaining a predetermined ratio between total air flow and fuel supply and between forced and induced draft, total air flow in this case being controlled by the two factors, namely, the forced draft fan 22 and the induced draft fan 30.

The system of control shown in Figure 2 is of relatively great simplicity as compared with devices of the prior art for accomplishing the same object.

The simple variable speed drive which I have recently developed and which is the subject matter of the aforesaid co-pending application, whereby

the speed of the fans may be varied smoothly and continuously throughout their working range, permits the correspondingly simple scheme of automatic combustion control which is herein shown.

This drive will now be described briefly in connection with the operation of the induced draft fan 30, shown at the left of Figure 2. This drive comprises a squirrel-cage motor 37 having the outer part which is usually the stator or case indicated at 38, mounted for rotation and having also the squirrel-cage rotor 39, the shaft of which squirrel-cage rotor 39 is connected to the drive shaft of the fan. The outer rotating member 38 is provided with windings which are supplied with alternating current through suitable slip rings.

A direct current machine 40 has a stationary field 42 and a rotatable armature 43, the shaft of which is connected to the outer rotatable member 38 of the squirrel-cage motor 37.

A D. C. generator 44 has a stationary field 45 and an armature 46, the armature 46 being connected in series with the armature 43 of the machine 40.

The armature 46 of the generator 44 is driven by an A. C. motor 47 which may be of any preferred type, as for example, either a squirrel-cage induction motor or a synchronous motor.

The main squirrel-cage motor 37 and the motor 47 of the motor generator set 48 are fed in parallel from the A. C. mains 49.

While I have shown three phase current supply and this is preferable, it is to be understood that I am not to be limited to three phase current as single phase or other type of alternating current supply may be employed.

The field of the D. C. motor 40 is separately excited from the D. C. constant potential supply mains 50. An adjusting rheostat 52 is inserted in the separately excited field circuit for the motor 40 for the purposes of adjustment. This rheostat 52 is suitably adjusted for operation within a certain range and then is not disturbed during variations of speed of the drive, except as the range is changed.

The separately excited field 45 of the generator 44 is supplied with a potential which is varied to control the speed of the drive. A potentiometer type of rheostat 53 is connected across the constant potential mains 50 and the terminals of the field winding 45 are connected to the brushes 54, 55, these brushes being adjusted as shown in the present instance by the pilot motor 56 and a suitable worm drive 57.

The squirrel-cage motor 37 provides the base speed and the direct current motor 40 which is of much smaller rating furnishes the increase or decrease in speed from the base speed.

The part 38 which is the case of the induction motor is mounted on bearings so that it may be rotated about the same axis as the rotor 39.

The case may be driven in either direction by means of the small D. C. motor 40, which draws power through the motor generator set 48. The speed of the D. C. motor 40 and its direction of drive are varied by varying the voltage of the generator 44 from maximum positive to maximum negative.

The speed of the fan 30 is increased above the base speed by causing the direct current motor 40 to drive the stator of the A. C. motor 37 in the same direction as the rotor. The speed of the fan then is the sum of the rotor and case speeds.

The speed of the fan 30 is decreased below the base speed by causing the case 38 to rotate in the opposite direction to that of the rotor 39.

It then drives the D. C. motor 40 as a generator, which forces power back through the series connection between the armatures 43 and 46 and through the A. C. motor 47 back on to the A. C. mains 49. The fan speed then is the difference between the rotor and case speeds. When the fan speed has reached the lower limit of speed by armature voltage control of the D. C. motor 40, the speed range may be extended still lower by field control at the rheostat 52 of the D. C. motor 40 if desired.

The H. P. ratings of the two motors 37 and 40 on the induced draft fan 30 are in the ratio of A. C. motor seventy-nine percent (79%) and D. C. motor twenty-one percent (21%) in one example of my invention.

The drive for the forced draft fan 22 is identical. However, the H. P. ratings of the two motors on the forced draft fan are in the ratio of A. C. motor 85.5% and D. C. motor 14.5%.

In practice I may employ several fans for forced draft and several fans for induced draft, as shown in Figure 1, in which case the motor generator set is common to the drives of the fans 30 and 30', but likewise the motor generator set for forced draft is common to the drives for the fans 22 and 22'.

The motor generator set for the drives 23 and 23', for fans 22 and 22' has the field of its generator 59 controlled by a rheostat 62 which is like the rheostat 53 and comprises a potentiometer winding connected across the constant potential direct current means 50 and having brushes 63 and 64 connected mechanically together and rotatable by the pilot motor 65 through the worm gear transmission 66. The brushes 63 and 64 are electrically connected to the terminals of the field winding of the generator 59. In all other respects the forced draft fan drives for the fans 22 and 22' are like the drives for the induced draft fans 30 and 30'.

The pilot motor 67 acting through a suitable worm gear transmission 68 shifts the contact brush 69 of the rheostat 72 for controlling the motor 12 of the coal feeder 10.

Instead of controlling the motor 12 directly, the pilot motor 67 and rheostat 72 may control the coal feed in any other preferred manner.

The pilot motor 74, through a suitable worm gear transmission 75, controls the position of the damper 19. This damper in the conduit 16 controls the rate at which primary air is supplied to the pulverizer for carrying the powdered coal into the furnace 3.

The steam pressure gauge 2 has a movable pointer 77 which, when steam pressure is properly maintained, lies between the increase and decrease contacts 78 and 79, this pointer 77 being connected to the negative bus of the D. C. supply mains 80. In like manner, the furnace pressure gauge 33 has a movable pointer 82 which operates as a selector contact between the increase and decrease contacts 83 and 84.

Similarly the CO₂ meter has a selector switch member 85 which operates between increase and decrease contacts 86 and 87, respectively.

The steam pressure gauge 2 indicates by movement of the pointer contact 77 to the left that steam pressure is falling and that the rate of firing should be increased. Likewise, if the pointer selector 77 moves to the right it means that steam pressure is building up and that the rate of firing should be decreased.

The furnace pressure gauge 33 likewise indicates by movement of the pointer 82 to the right

that the pressure in the furnace has decreased below its predetermined value and movement of the pointer 82 to the left indicates that the furnace pressure has increased above the predetermined value.

The CO₂ meter 34 which represents proper ratio of air to fuel indicates by movement of the pointer 85 to the left that the rate of coal feed should be increased, and indicates by movement of the pointer 85 to the right that the rate of coal feed should be decreased.

I provide a series of increase and decrease circuits between the steam pressure gauge and the pilot motors of the induced draft control rheostat 53, pilot motor 65 of forced draft rheostat 62, pilot motor 67 of the rheostat 72 for controlling coal feed, and pilot motor 74 for controlling the damper of the primary air.

The pilot motor 56 has a forward drive circuit wire 88 and a reverse circuit wire 89. Common return wire 90 is connected to all of the pilot motors.

In like manner the forced draft fan pilot motor 65 has a forward drive wire 92 and a reverse drive wire 93. The pilot motor 67 has a forward drive wire 94 and a reverse drive wire 95. The pilot motor 74 has a forward drive wire 96 and a reverse drive wire 97.

The branch control wires are extended to relay contacts of the steam pressure gauge, the furnace pressure gauge and the CO₂ meter, respectively.

The forward contact 78 at the steam pressure gauge 2 controls the relay winding 98 of the increase relay 99. The contact 79, on the other hand, controls the relay winding 100 of the decrease relay 102. A series of four wires, 103, 104, 105 and 101 lead to the forward wires 88, 92, 94 and 96, respectively, of the pilot motors 56, 65, 67 and 74.

Likewise a series of branch wires, 106, 107, 108 and 109 lead respectively to the decrease or reverse wires 89, 93, 95 and 97 of the pilot motors 56, 65, 67 and 74.

The furnace pressure meter 33 has a pair of relays 110 and 112 controlled by contacts 83 and 84, respectively, under the influence of selector switch pointer 82 for closing forward and reverse branch circuits 113 and 114, respectively, to the forward and reverse wires 88 and 89 of the induced draft pilot motor 56, respectively.

The CO₂ meter 34 has a pair of relays 115 and 116 under the control of contacts 86 and 87, respectively, as selected by the selector contact pointer 85. These relays control branch circuits 130 117 and 118, respectively, leading to the forward or increase and reverse or decrease wires 94 and 95, respectively, of the pilot motor 67 for coal feed.

Since these various gauges 2, 33 and 34 might at the same time impose conflicting requirements upon the pilot motors which would result in short circuiting of the system, I interpose the timing controller 120, the details of construction of which are shown in Figures 3 and 4. This timing controller, as diagrammatically indicated in Figure 2, comprises a rotatable shaft 122 upon which are mounted a series of circular discs bearing conducting segments and engageable by brushes. These discs with segments, together with their brushes, constitute commutators or switching devices all in timed relation to each other. Thus the disc 123, which bears a conducting segment 124, has cooperating brushes 125 for closing the branch circuit 103.

The brushes 125 are adjustable relative to each other and angularly about the axis of the shaft 122 so as to control not only the exact time at which the circuit is closed and/or opened, but also the duration of time of such closing and/or opening. The commutator 126 is connected in the branch wire 113 between the forward induced draft wire 88 and the furnace pressure gauge 33. The commutator 127 is connected in the branch wire 104 between the steam pressure gauge and the forward or increase wire 92 for forced draft. The commutator 128 is connected in the branch circuit 105 leading to the forward wire 94 for coal feed. The commutator 129 is connected to 15 the branch wire 117 between the CO₂ meter 34 and the forward or increase wire 94 of coal feed. The commutator 130 is connected in the branch 101 leading to the forward wire 96 of the primary air control dampers. A number of spare commutators 132 on the increase end of the timing controller 120 are shown. In fact, as many commutators as may be required may thus be mounted upon the shaft for either increase or decrease 20 operation of the respective pilot motors or other electro responsive devices or the like.

The reverse end or decrease end of the shaft 122 bears a series of commutators 133, 136, 137, 138, 139 and 140 which are connected in the reverse or decrease branches in the same order as 30 the forward or increase commutators 123, 126, 127, 128, 129 and 130, above described.

Now it is to be observed that in the timing controller 120 the conducting segment such as 124 of the commutators 123, 127, 128 and 130 are 25 all of approximately the same angular extent and are disposed in the same angular relation. These are on the increase end of the shaft. The contacts of the commutators 133, 137, 138 and 140 correspond in angular extent and angular position with the group above mentioned, namely, 123, 127, 128 and 130. It is obvious that the selector contact 77 of the steam pressure gauge 2 can cooperate with only one at a time of the forward and reverse contacts 78 and 79, respectively.

The brushes for each commutator are, however, adjustable toward or away from each other so as to increase or decrease the duration of contact. Preferably, but not necessarily, they 50 terminate contact at approximately the same angular position so that the common return relay contact 143, may, under the influence of the commutator 144 and relay 145, break the common return wire 90 and thereby relieve the contactors or commutators of arcing.

The commutators 126 and 129 on the increase end and the commutators 136 and 139 on the decrease end have conducting segments of substantially the same angular extent and position. Their brushes likewise are adjustable with respect to each other to increase or decrease the duration of contact.

The shaft 122 is rotated in a clockwise direction as viewed from the left-hand end and as indicated by the arrow adjacent said left-hand end.

The shaft 122 is rotated by a motor 146 through back gears 147 and the circuit of the motor 146 is under the control of a rheostat 148 and a commutator 149, the purpose of which is to cut the rheostat 148 in and out of circuit with respect to the driving motor 146 so as to change the angular rate of motion of the shaft 122 for different parts of a rotation. That is to say, the commutator 149 preferably has a conducting seg-

ment corresponding with the angular extent of conducting segments on the active commutator discs so that the rate of motion of the motor 146 is increased as the contacts arrive under the brushes and then the shunt about the rheostat 143 is opened and the rheostat 148 thrown into the circuit with the motor 146, causing it to slow down and thereby drive the shaft 122 through the remainder of its rotation at a slower speed so as to introduce a desired interval of waiting.

It will be observed that the brushes of the commutator 144 are so disposed that the segment breaks the circuit in each case just before corresponding branch circuits are broken at the other commutators, in order to permit the common return wire 90 to be interrupted so as to relieve each set of contacts of the duty of breaking the respective current flows. Thus, arcing at the controllers or commutators is avoided.

Now it is to be observed that in the orderly sequence of events a test is made of furnace pressures and carbon dioxide by closing both forward and reverse branch wires at the respective commutators 126, 136 and 129 and 139, respectively, to detect any deviation of furnace pressure from the selected or predetermined standard and to detect any deviation of CO₂ from the predetermined standard, either above or below the standard.

If the indicator or selector contacts 82 and 85 stand in neutral, nothing happens. If the selector contacts 82 or 85 close one or the other of the selectable circuits, then the induced draft or the coal feed may be varied as determined by the selector contact.

Thereafter the circuits for the steam pressure gauge contacts are closed to test whether an increase or decrease of firing is required. Since the selector contact 77 can co-act with only one of its pair of contacts and since the circuits of the pilot motor leading to the pressure gauge 22 are closed only after the circuits for the furnace pressure gauge and CO₂ gauge or meter are closed, no conflict can occur.

After the testing of the steam pressure gauge the commutator 149, which controls the speed of the motor 146, acts to interpose a period of waiting before the next period of test is made.

The timing controller thus performs several functions.

1. It permits the pilot motors to turn their respective rheostat arms for a period, then it cuts them out of service for a period, thereby giving the furnace time to respond between the application of successive impulses. An adjustable rheostat which is cut into and out of the circuit of the motor which drives the intermittent contact device mechanism with the "on" and "off" switching of the pilot motors regulates the ratio of the time between successive impulses.

2. It permits an independent adjustment of the time each pilot motor is in circuit, with respect to the other pilot motors. This adjustment is made by moving the upper contact finger shown in Figure 4 up or down on its support.

3. It prevents the simultaneous closing of the increase and decrease circuits. It will be noted that the increase or decrease contactors of any given gauge cannot be closed simultaneously as the gauge can make contact in but one direction at a time. Two different gauges may, however, simultaneously call for opposite actions on one of the pilot motors. For example, the steam pressure gauge may call for increased speed from

the induced draft fan while the furnace pressure gauge may call for decreased speed. This is prevented by staggering the corresponding segments on the shaft so that the impulse of the 5 second gauge is not transmitted to the pilot motor until after the first gauge has completed the transmission of its impulse.

In Figures 3 and 4 I have shown an embodiment of the timing controller in which the segments employed are all alike and interchangeable. They are so designed that in assembling 10 them on the shaft 122 the leading end of the leading segment corresponds to the trailing end of the trailing segment.

15 While I have shown two sets of segments all in register this is not essential but it forms a desirable embodiment for my present purposes.

Referring now to Figures 3 and 4, I have shown 20 herein a specific embodiment of the timing controller.

The shaft 122 is shown herein as a square shaft supported at its ends in suitable bearings, one of which is shown at 152 mounted upon the insulating base 153. This base has a rectangular opening 154 formed therein through which the individual commutator segments or 25 contactors project. The motor 146 is back geared to the shaft 122 through gears 147 comprising a suitable countershaft for reducing the motion of the motor shaft to a suitable speed for 30 the operation of the contactors.

While in the diagram of Figure 2 the commutator elements are shown as discs of insulation bearing conducting segments in the construction shown in Figures 3 and 4, the conducting segments are formed integral with supporting arms such as the arm 155 having a clamping foot or hub portion 156 formed integral therewith.

40 A cooperating cap or strap 157 is bolted to the clamping portion 156 as by means of the bolts 158, 158. In the case of the circuit controllers 144 and 149, two such metal segments have their hub portions bolted together so that 45 the arcuate contact portions 159 and 160 for the controller 144 are in the same plane. Likewise the contacting portions 162 and 163 for the controller 149 are in the same plane. The square shaft 122 is provided with a sleeve 164 of insulation so as to insulate all of the controllers 50 from each other.

Each circuit controller is provided with a pair of brushes of which the pair 165, 166 is typical. The brush 165 comprises a clamp portion 167 which is mounted upon the arcuate rod support 55 168, the ends of which rod 168 are bolted or otherwise secured to the insulating base 153. Each controller has such a brush supporting arcuate rod.

60 The clamping member 167 is provided with a wing nut 169 by which the split clamp of the clamping portion 167 may be released or tightened to change the position upon the rod 168 to vary the angular position of the contactor 65 brush 170 which is pivotally mounted as at the pivot 172 upon the clamping portion 167.

The clamping portion 167 makes electrical contact with the arcuate supporting rod 168 and this rod in turn is connected to a circuit terminal, as indicated at 173. The end of the rod forms a suitable binding post as indicated at 70 174, 174 for connecting the circuit wire 173.

75 The brush member 166 is of a construction similar to the brush 165 with exception that it is insulated from the supporting rod 168 by a sleeve

175 of suitable insulating material. This brush 166 is intended to be relatively stationary although it has a small degree of adjustment in the form shown. Naturally if desired a sufficiently long flexible lead may connect the brush member 166 with the stationary binding post 176 to permit of any desired degree of adjustment of the position of the brush 166. As shown the brush 166 is connected to the binding post 176 by a lead 177 and the post 176 is connected to a circuit wire 178 upon the opposite side of the board.

I have shown a square shaft, since in the particular timing controller which I employ herein eight different positions of a contactor segment may be secured as it will be observed that the arm 155 is angularly disposed with respect to the diagonals of the square shaft 122 so that by disposing the arm 155 on one side or the other of the adjacent corner of the shaft 122, a suitable variation in angular position may be secured to make up the 80 eight separate positions in which the contactor 85 may be disposed on the axis of the shaft 122.

Obviously I do not intend to limit the invention to this specific construction as the shaft may be a round shaft provided with suitable splines or otherwise constructed to provide predetermined seats or shoulders or grooves for aligning the contactors in a predetermined manner.

It can be seen that as the motor 146 rotates the shaft 122 through the reduction gears 147 the 90 circuits are controlled as follows:

The circuit is broken at the contact 143 in the common return 90 by the controller 144, then a period of waiting occurs to permit the adjustment which has previously been made, to take effect. 95 Then the controllers 126, 136, 129 and 139 close their contacts for the induced draft control and coal feed control, respectively. If the furnace pressure gauge 33 closes either the increase or decrease circuits, a corresponding adjustment of the pilot motor 56 will be made. Likewise, if the 100 carbon dioxide gauge 34 closes its circuit for increase or decrease, a corresponding action of pilot motor 67 will occur.

Immediately thereafter the circuit is broken at 105 contact 143 to relieve the controllers 126, 136 or 129, 139 of breaking the connection, and then immediately thereafter the circuit is again established to prepare for the test of steam pressure which thereupon occurs. The test for steam 110 pressure closes the circuit for all four pilot motors both for increase and decrease and the steam gauge selector contact 77 selects which if either 115 action is to occur. Just before the contacts are broken at the controllers the common return contacts 143 are again opened to relieve the controllers of the duty of breaking the current flow.

It will be observed that the brushes of the controller 144 are set close to each other and are in a predetermined angular position with respect to 120 all of the other controllers so that the circuit is broken at the brushes of the controller 144 just in advance of breaking the circuit at any of the other controllers.

I wish to call attention to the fact that theoretically the timing controller would not need to be connected in the individual branch circuits of the pilot motors but might be connected merely in the common return branches 182, 183 and 184 for the selector switches of the gauges 2, 33, and 34. 125 However, it would be then impossible to make the different relative adjustments between the actions of the various pilot motors in response to the action of each gauge as is possible in the system as shown. That is to say, in the present scheme, as 130 135 140 145 150

shown in Figure 2, by adjustment of the brushes of the individual controllers relatively greater or less action of the corresponding pilot motors may be secured for each "on" period. For example, 5 consider the controllers 123, 127, 128 and 130. It may be desirable to have the pilot motor 74 make a larger number of revolutions than some of the other pilot motors. If so, the brushes for the contactor 130 are moved closer together so as to 10 give a longer period of closed circuit for the said motor 74. Thus individual adjustments of the response of the various pilot motors for the control of each gauge may be made to secure optimum conditions in the responsive apparatus.

15 It is to be observed that the variable speed drive of my invention is capable of simple rheostat control and for a given position of the controlling rheostat a fixed speed will be held by the drive. In this manner, due to the simplicity of 20 the control of speed of the large power units, as well as of the small power units, a simplified system of control is made possible.

In compliance with the requirements of the 25 patent statutes I have herein shown and described a preferred embodiment of my invention. It is however to be understood that the invention is not limited to the precise arrangement herein disclosed, the same being merely illustrative of the 30 principles of the invention. What I consider new and desire to secure by Letters Patent is pointed out in the appended claims:

I claim:

35 1. The method of regulating the movement of air through a furnace having forced draft and induced draft which comprises periodically adjusting the value of both forced and induced draft according to a fixed ratio, and periodically adjusting the relative values of forced and induced draft between periods of simultaneous adjustment of the values of the same.

40 2. The method of regulating combustion in a furnace having air supply controlled by forced draft and induced draft and having coal feed, which comprises, comparing total combustion with a predetermined standard, making a definite step of adjustment of the values of air supply and fuel feed in the direction determined by said comparison, comparing the ratio of forced draft to induced draft with a predetermined standard and making a definite step of adjustment of the relative values of forced to induced draft in a direction determined by said comparison, said steps of adjustment being made during separate 45 periods of time occurring in an orderly progression.

50 3. The method of regulating combustion in a furnace having air supplied by forced draft and induced draft and having coal feed which comprises comparing total combustion with a predetermined standard, making a definite step of adjustment of the value of air supply and fuel feed in the direction determined by said comparison, comparing the ratio of forced to induced draft with a predetermined standard, making a definite step of adjustment of the relative values of forced to induced draft in a direction determined by said comparison, comparing the ratio of air feed to fuel feed with a predetermined standard and making a definite step of adjustment of the ratio of fuel to air in the direction determined by said comparison, certain of said steps of adjustment being made during periods of time occurring alternately in an orderly progression.

75 4. In a system of combustion, the method of

controlling a plurality of inter-related actions which control a common resultant which comprises comparing the absolute value of the resultant action with a predetermined standard, positioning a responsive element in accordance with said comparison, periodically testing at predetermined intervals the position of said responsive element with respect to a predetermined standard position and simultaneously varying the absolute values of a plurality of the inter-related actions in a direction determined by the deviation of the position of said responsive element from said standard position, comparing the relative values of two of said inter-related actions, positioning a second responsive element in accordance with said second comparison, periodically testing at predetermined intervals which intervals alternate between intervals of the first periodical tests, the position of said second responsive element with respect to a predetermined standard position, and simultaneously with said second intervals of testing varying in a direction determined by the position of said responsive element the relation between said two last named actions.

100 5. In a system of the class described a plurality of devices having inter-related actions, a plurality of controllers governed by the inter-related actions of said devices, regulators for said devices adjustable by said controllers, and means for subjecting certain of said regulators to the action of different controllers in predetermined sequence.

105 6. In a system of combustion, a plurality of devices having inter-related actions controlling a common resultant action, an element responsive to the deviation of the resultant action from a predetermined standard, a first means controlled by said element for regulating the action of said plurality of devices to vary the resultant action, a second element responsive to the deviation of the relation between the actions of two of said devices from a predetermined standard, a second means controlled by said second element for regulating the action of one of said two last named devices to vary the ratio of their action, and a 110 timing controller for allowing said first means and said second means to act alternately for predetermined periods of time.

115 7. In a boiler control the combination of air supply means, fuel feeding means, a steam pressure gauge, a combustion efficiency meter, adjusting devices for the air supply means and the fuel feed means subject to the control of the steam pressure gauge and the efficiency meter and a timing control for permitting the steam pressure 120 gauge to govern the adjusting devices for predetermined periods of time, said timing controller permitting the efficiency meter alternating between periods of control by the steam pressure gauge to control one of the adjusting devices.

125 8. In a combustion control system induced draft supply means, forced draft supply means, fuel feed means, a gauge responsive to conditions affected by the combustion, a gauge responsive to the efficiency of combustion, a gauge responsive to the relation between induced draft to forced draft, adjusting devices for individually adjusting the induced draft supply means, the forced draft supply means and the fuel feed means, a timing control having a means for periodically regulating the adjusting devices in accordance with variations of the first mentioned gauge, and having means for periodically regulating one of said adjusting devices in accordance with the efficiency of combustion gauge, and having means

- for periodically regulating one of said adjusting devices in accordance with the draft ratio gauge, the first, second and third recited means of the timing control acting in predetermined order.
5. 9. In a combustion control system air supply means, fuel feed means, adjusting devices for said means comprising rheostats, a gauge responsive to conditions affected by the combustion, a gauge responsive to efficiency of combustion, electro-
10 magnetic regulating means for the respective ad-
justing devices, electrical circuits from one of the gauges to both of the regulating means and from the other gauge to at least one of the regulating means and a timing controller for switching the
15 circuits to permit each of the gauges to exercise control in predetermined order.
10. In combination, a forced draft fan, a variable speed electric drive therefor, an induced draft fan, a variable speed electric drive therefor,
20 a coal feeding device, a variable speed electric drive therefor, individual rheostats for said variable speed drives, reversible electromagnetic de-
vices for adjusting said rheostats, a gauge re-
sponsive to conditions affected by the combus-
25 tion, a gauge responsive to the ratio of forced draft to induced draft, a gauge responsive to ef-
ficiency of combustion, selector contacts gov-
erned by said gauges, forward and reverse cir-
205 cuits from said gauges to certain of said devices controlled by said selector contacts, and a timed sequence controller for closing certain of the cir-
250 cuits in predetermined sequence.
11. In a system of the class described, the combination of a plurality of controlling devices, a plurality of controlled devices of which one controlled device is subject to control by more than one controlling device and a sequence timing controller for subjecting said one controlled de-
30 vice to the control of said controlling devices in predetermined sequence.
12. In a system of the class described, the combination of a furnace, an induced draft fan, a forced draft fan, a furnace pressure gauge, alternating current mains, variable speed drive units operated by current from said mains for driving said fans at variable speeds extending throughout the range of operation of the furnace, rheostats for varying the speeds of said drive units, said units having definite speeds for definite po-
45 sitions of the rheostats and means controllable by said furnace pressure gauge for shifting the rheostat of the drive unit of one of the fans to maintain a desired ratio of induced draft to forced draft.
- 55 13. In a steam generating plant, a boiler, a furnace, an induced draft fan, a forced draft fan, a furnace pressure gauge, a steam pressure gauge, attending current mains, variable speed drive units including squirrel cage A. C. motors operated by current from said mains for driving said fans at speeds which are variable throughout the range of draft required, potential control rheostats for varying the speeds of said drive units in any desired degree within the range of control, said units having definite speeds for definite positions of the rheostats and means for subjecting said rheostats periodically to the control of the steam pressure gauge and between each period subjecting one of the rheostats to the control of the furnace pressure gauge.
14. The method of regulating a plurality of in-
terrelated actions controlling combustion, which comprises periodically adjusting the values of two of the actions in fixed ratios and between the periodic adjustments adjusting the relative
80 values of said two actions.
15. The method of regulating a plurality of in-
terrelated actions controlling combustion, which comprises measuring variations in the ratio of the load demand to the output, periodically mak-
ing an adjustment of the factors of combustion in fixed ratios in accordance with the variations, measuring the efficiency of combustion, and alternately with said periodic adjustments adjust-
ing the fuel to air ratio in accordance with the
90 variations in efficiency of combustion.
16. In a combustion control system means for feeding one of the elements of combustion, means including an adjustable rheostat for ad-
justing rate of feed, means responsive to prede-
termined conditions for adjusting the rheostat at a constant rate, means for periodically inter-
rupting said last named means, and means for
varying the ratio of duration of periods of ad-
justment and periods of interruption.
95 100
17. In a combustion control system means in-
cluding pilot motors for controlling the rates of feeding of the elements of combustion, means re-
sponsive to the conditions of combustion for ad-
justing said pilot motors at a constant predeter-
mined rate, a timing controller for periodically in-
terrupting the adjusting of the pilot motors and variable rheostat means for adjusting the
105 duration of the periods of interruption.
18. In a combustion control system a plurality
110 of devices having interrelated actions control-
ling a common resultant action, an element re-
sponsive to the deviation of the resultant action from a predetermined standard, a first means controlled by said element for regulating the
115 action of said plurality of devices to vary the resultant action, a second element responsive to the deviation of the relation between the actions of two of said devices from a predetermined
120 standard, a second means controlled by said sec-
ond element for regulating the action of one of said two last named devices to vary the ratio of their action, a timing controller for allowing said first means and second means to act alternately
125 for predetermined periods of time together with
periods of rest or inactivity, and means for ad-
justing the relative durations of times of action and of rest.
19. In a combustion control system, a furnace, air supply means, fuel feeding means, a device responsive to heat demand on the furnace, a combustion efficiency meter, adjusting devices for the air supply means and the fuel feed means subject to the control of the demand responsive device and the efficiency meter, a timing con-
troller for permitting the demand responsive de-
vice to govern the adjusting devices for predeter-
mined periods of time alternating with periods of
control of one of the adjusting devices by the effi-
ciency meter and periods of interruption for al-
lowing conditions to equalize, and adjustable
135 means for varying the relative durations of pe-
riods of control and periods of interruption.
140 145

ALLEN M. ROSSMAN. 145
